T. MEIN.

TABLE COVER, &c.

No. 21,010.

Patented Aug. 25, 1891.

UNITED STATES PATENT OFFICE.

TURNER MEIN, OF PHILADELPHIA, PENNSYLVANIA, ASSIGNOR TO JOHN BROMLEY & SONS.

DESIGN FOR A TABLE-COVER, &c.

SPECIFICATION forming part of Design No. 21,010, dated August 25, 1891.

Application filed July 15, 1891. Serial No. 399,644. Term of patent 3½ years.

To all whom it may concern:

Be it known that I, TURNER MEIN, a subject of the Queen of Great Britain, residing at Philadelphia, in the county of Philadelphia and State of Pennsylvania, have invented a certain new and original Design for a Table-Cover or Curtain, of which the following is a specification, reference being had therein to the accompanying drawing.

My invention relates to the surface ornamentation of a table-cover or curtain; and it consists of the design therefor illustrated in the accompanying photographic drawing.

I claim as my invention—

The design for a table-cover or curtain, substantially as shown and set forth.

In testimony whereof I have affixed my signature in presence of two witnesses.

TURNER MEIN.

Witnesses:

WM. L. TURNER,
EDWARD BROMLEY.
